Des. 239,277

Patented Mar. 23, 1976

239,277

BUILDING STRUCTURE

Kreso Forgiarini, 2998 N. Lake Ave.,
Altadena, Calif. 91001

Filed May 30, 1974, Ser. No. 474,516

Term of patent 14 years

Int. Cl. D25—0.3

U.S. Cl. D13—1 B

FIG. 1

FIG. 4

FIG. 5

FIG. 2

FIG. 3

FIG. 1 is a perspective view of a building structure in accordance with this invention;

FIG. 2 is a side elevational view of the structure of FIG. 1;

FIG. 3 is a front elevational view of the structure of FIG. 1;

FIG. 4 is an elevational view of the opposite side from that shown in FIG. 2; and

FIG. 5 is a rear elevational view of the structure of FIG. 1.

I claim:

The ornamental design for a building structure, as shown.
